(57) **CLAIM**

I claim the ornamental design for outsole for a shoe, as shown and described in the drawings. It is understood that the surface of the heel is, with the exception that the heel is without ridges, the same as shown in the cross sectional view of FIG. 6.

DESCRIPTION

FIG. 1 is a bottom view of an outsole in accordance with the new design;

FIG. 2 is a left view of the outsole in accordance with the embodiment of the new design shown in FIG. 1;

FIG. 3 is a right view of the outsole in accordance with the embodiment of the new design shown in FIG. 1;

FIG. 4 is a front view of the outsole in accordance with the embodiment of the new design shown in FIG. 1;

FIG. 5 is a back view of the outsole in accordance with the embodiment of the new design shown in FIG. 1; and,

FIG. 6 is an enlarged cross-sectional view taken on line 6—6 of FIG. 1.

The broken line showing a shoe upper in FIGS. 1–5, and showing the interior surface in FIG. 6 illustrate the portions of the design that form no part of the claim.
